UNITED STATES PATENT OFFICE.

ELIHU THOMSON, OF LYNN, MASSACHUSETTS.

SYSTEM OF ELECTRIC DISTRIBUTION.

SPECIFICATION forming part of Letters Patent No. 322,139, dated July 14, 1885.

Application filed April 27, 1885. (No model.)

To all whom it may concern:

Be it known that I, ELIHU THOMSON, a citizen of the United States, and a resident of Lynn, in the county of Essex and State of 5 Massachusetts, have invented certain new and useful Improvements in Systems of Electric Distribution, of which the following is a specification.

The present invention relates to an improved method of and apparatus for operating electric incandescent lamps or other similar appliances from an induced current generated in a secondary coil of an induction-coil, the primary coil of which is intermittently 10 traversed by a current derived from a main line—such as a constant-current line—upon which are lamps or other devices are operated.

One of the objects of my invention is to 20 provide a means whereby a high potential line of great length conveying a moderate current—such as ten ampères—may be used successfully to operate one or more incandescent lamps or other apparatus placed at any convenient point, and requiring no great electro-motive force for their successful operation, without involving the presence upon the lines connected to the lamps of high and dangerous potentials existing on the main line, and 25 to also permit the extinction and relighting of such lamps without affecting the continuity of the main-line current.

My invention is applicable to cases where 30 more or less energy of a continuous line-current is to be utilized upon a secondary local line—such as a domestic installation of incandescent lights. The means whereby these objects are secured are described and shown in the accompanying figures.

Figure 1 is a diagram of the essential parts of the invention. Fig. 2 is a diagram showing further extensions of the apparatus. Figs. 3, 4, 5, and 6 show various parts of my invention; Figs. 7 and 8, modified constructions; 40 Figs. 9, 10, and 11, further modifications of the apparatus and devices. Fig. 12 shows a detail of arrangement.

In Fig. 1, X Y indicate portions of the main line, in a branch of which is inserted a secondary battery of one or more cells, B, whose terminals are connected, as shown, to X and Y, respectively. Another branch from X to

Y passes through a coarse-wire primary coil, P P, wound upon an iron wire or other core, I, and through a set of contacts (indicated at 55 K) and of any desired kind, arranged to be opened and closed at rapid intervals in any suitable way so as to frequently and regularly interrupt the branch through P P. This may be accomplished by an armature arranged to 60 be attracted by the core I to open contacts K, the contacts being closed, on the loss of magnetism of I, by means of an elastic spring, a device which is common in induction-coils. A secondary wire coil, S, is wound around the 65 iron core I in any suitable manner and kept insulated from the primary wire P P. The relative sizes and proportions of the parts I, P, P, and S will depend upon the amount of energy to be transferred and other considerations 70 known to electricians. The wire S in the case illustrated is of sufficient length and fineness to afford requisite electro-motive force to operate an incandescent lamp or lamps, L, inserted between its terminals. A shunting or 75 other switch, W, is provided at any convenient point for extinguishing the lamp L. Such switch might be made to introduce a variable resistance or equivalent device for diminishing the lighting power of L, and, if desired, 80 finally shunting it. In some cases I use a condenser, C, whose foils are respectively connected to the contacts K, though such condenser is not always applied. The condenser is sometimes useful in moderating the spark 85 at the contact K.

As shown in Fig. 2, two or more distributing devices may be connected in series in a line and will operate independently to deliver secondary or induced currents to the lamps 90 L L or other devices, two or more of which may be fed from a single secondary coil and in series or in multiple arc.

A means for varying the delivery of currents is shown at the right hand of Fig. 2, at 95 R. It consists of a coil connected to the secondary circuit and provided with a movable core. The coil and core act by self-induction and according to the position of the core, either in or out of the coil, to permit the discharges from the secondary to pass with more or less freedom through it. The battery B, in Fig. 1, need only be of simple construction. It may consist merely of plates of metallic

lead or hard carbon immersed in dilute sulphuric acid. A simple cell (shown in Figs. 3 and 4) consists of an outer vessel of lead, D, or other polarizable material, holding 5 liquid, and an inner plate of lead, E, immersed in dilute sulphuric acid contained in D, and kept from touching D. Any number of these cells may be connected in series or multiple arc to form battery B, Fig. 1.

10 It is to be understood that any battery capable of polarization or accumulation by the line-current on X Y may be used. Any proper surfaces, as of sheet lead of any desired formation or arrangement in a cell, are quite 15 sufficient for the purposes of my invention, the function of the battery being simply to acquire a small surface polarization by the current from the main line X Y, and to be capable of a vigorous discharge of the accumulated 20 current when the circuit is closed between the terminals.

Fig. 5 illustrates more in detail the parts of the induction-coil shown in Fig. 1. I is the iron wire or sheet iron core, around which 25 the primary wire P and a secondary, S, are coiled. An armature, N, mounted on a spring, n, is arranged, when attracted toward the core I, to open the contacts at K, which contacts are composed of some known non-oxidizable 30 and good conducting metal, as usual in such cases. The contact carried by N is preferably made so that it may be changed in position, when desired to present new surfaces for use, as indicated in dotted lines, Fig. 6. It is 35 also made so as to be readily replaced or renewed. To these ends it may consist simply of metal plate fastened to the spring by a screw, as shown. The contact opposed to it is also made so as to be readily replaced or 40 renewed.

Before describing further parts of my invention it will be convenient to set forth the mode of operation of the appliances shown in Fig. 1. Assuming a continuous current to 45 traverse the line from X to Y, and that the contact K is momentarily opened, the said current, finding a path only through the battery B, will charge or polarize said battery in such manner that when the contacts K are 50 closed a current would pass from the left hand of said battery in the figure and join the main current from X, and adding itself thereto, will pass through the primary coil P P, the main-line current going to Y and the battery current being closed upon itself through P P. 55 At this moment a current will pass through P P far exceeding in amount that of the main current. The circuit-breaker, however, at once opens the contacts K by the core I attracting the armature N, Fig. 5. The primary current is thus interrupted, while the line-current Y is again forced to charge the battery B. An adjustment of the contact at K can readily be made such that an automatic 60 opening and closing of the contact will take place with a rapidity depending on the elastic force of the armature carrying spring n and

the weight of the armature N. This should be arranged to give a very rapid vibration, and the contact K should be adjusted to open 70 when the current through the primary P P is not too intense. If adjusted to require a too strong current, they would prevent the continuous action by totally discharging the battery B. The proper conditions can readily be 75 found by which a continuous induction will take place in such manner that the secondary coil S will deliver rapidly-alternating currents through the lamp L so as to keep it lighted. The shunting-switch W serves to extinguish the light by short-circuiting the secondary coil S, in which case the abstraction 80 of energy from the main line becomes less than when the lamp L is burning, in consequence of the development of less extra current in the primary P P—indeed, the contact-breaker will sometimes soon discontinue its vibration after the switch W is closed, and the main-line current from X to Y will pass unhindered through the primary P P. To 85 start the device the contact K must again be opened to permit recharging of the battery B, when, if the switch W be opened, the light L will continue to burn, as before. I sometimes arrange the secondary coil in sections, 90 as shown at A', B', C, and D' in Fig. 7, with switches for connecting such sections in series, multiple arc, or in multiple series. By attaching small insulated plates a b c d, 95 respectively, to one terminal of each coil A' B' C' D', and plates e f g h to the other corresponding 100 terminals of A' B' C' D', wound in the same direction, and inserting plugs between a b, b c, and c d, also between e f, f g, and g h, the multiple-arc connection is had, while by removing such plugs and inserting them between b e, c f, and d g a series connection is had. Other connections are possible by proper use 105 of plugs. Wires leading to the lamps are attached to a and h, the extremes of the series 110 which constitute the terminals from the secondary coil.

It is sometimes preferable to operate the contacts K mechanically, as by clock-work, or by other motor mechanism, such as an electric motor. In Fig. 8 I have indicated in general such plans of operation. P represents the primary, one of the contacts at K being attached to it, and one of them being made movable by being carried upon a sheet-metal 115 spring, n, or otherwise mounted so as to be moved toward and from the fixed contact by the rotation of the toothed wheel W, set in motion by a weight, coiled spring, or other clock-work appliances, or any source of power. 120 The passage of the toothed wheel over the projection carried upon the spring n suffices to give the requisite movement to the contact. Many other devices might be substituted with 125 similar results. However, it is most convenient to cause the current itself to directly operate the contacts. The devices of Figs. 1 and 5 only do this after the battery B has been allowed to receive a charge by keeping the con-

tacts open for a moment at the start. To obviate the necessity of this I have devised a modification (shown in Fig. 9) in which a circuit through the battery branch from X to Y 5 contains a small electro-magnetic coil, F, wound upon a suitable core opposite to which is mounted an armature, N, which, on being attracted toward the electro-magnet F, closes the contacts K, which complete a branch from 10 X to Y through the primary coil P. When the armature M is released, the contacts K are opened by a spring which draws away such armature M. For certainty of action the armature M should be polarized or permanently 15 magnetized, so that it would be attracted toward F when the line-current from X to Y is passing through the battery only, and will be repelled when the line-current, plus that of the battery, is passing through the primary 20 coil of P.

In Fig. 10 the modification of the parts shown in Fig. 9 is seen, in which the polarization of the armature M is secured by winding upon it or placing near it a coil so connected as to be always in the main-line current from X, the current only branching from the contact K and to the magnet F after leaving the polarizing-coil. In other respects the devices are the same as just described. 25 Under such circumstances the following connections will ensue: The contacts K will be opened at the start, and current will pass through F and B from X to Y, causing the armature M to close the contact K. At this 30 moment the current will pass from X to Y through the contacts K and the primary coil P, while the battery will also discharge current through the magnet F, the contacts K, and coil P, and will assist the main line in reversing the magnetism of M. The armature M will therefore be repelled, the contacts K will open, and the battery B again receive a charge from X to Y, and the former connections will be continuously repeated with a rapidity depending upon the elasticity and 45 inertia of the contact-maker.

In Fig. 11 another style of contact-breaker and operating device is shown. It consists of an electro-magnet, F', placed in the main-line current, which magnet upon attracting its armature N opens the primary circuit contact K, at the same time closing a contact, Q, which forms a shunt around the magnet-coil by establishing a circuit through the armature direct to the pillar W². When the contacts at Q and at K are open, the circuit passes from X to lower contact, Q, through the coils of F' to the pillar supporting the armature N, from said pillar to the battery branch B to Y, and from said pillar through the contacts K, when closed, and the primary coil P. By these connections, F' is shunted when N is attracted, the result being a continuous and rapid vibration, and closure and opening of the contacts K and Q alternately. In all other essential features the devices are the same as before described, except that the apparatus

in Figs. 9, 10, and 11 are self-starting and entirely automatic.

It is desirable that the main line from X to Y should have inserted in it an absolute cut-off of any desired kind located at l, Fig. 12, by means of which a complete shunting and absolute cut-off of the loop in which the battery B, primary coil P, and contacts K are placed may be effected when such devices are to be thoroughly cut off from the circuit. 75

Having now described the present invention, I wish it understood that I do not limit myself to the particular form of apparatus shown in the figures, but may employ any other equivalent forms known in the art yielding equivalent results, my invention consisting of a particular method of continuously operating an induction apparatus from the main-line current—such as used in arc lighting—at the same time securing independent currents on a local circuit, or secondary coil from connection with the high-potential main, and also securing great ease of manipulation and 90 simplicity of parts.

What I claim as my invention is—

1. The combination, with a main-line circuit, of one or more devices consisting, substantially, of a branch containing a secondary battery, B, and another branch containing a primary coil, P, and circuit-interrupting contacts, whereby induction discharges are obtained in a secondary coil, S, connected to a separate circuit, substantially as described. 100

2. A main or supplying line for electric currents, having a derivation into two branches, one containing a secondary battery, and the other a primary coil and circuit-breaking contact, as set forth, in combination with a secondary coil connected to a local independent circuit containing electric lamps or other translating devices. 105

3. The combination, with the main line and induction coil, of a branch around the induction apparatus, in which branch is placed one or more cells of a battery consisting simply of polarizable surfaces immersed in conducting liquid, and of a secondary coil connected to a local circuit. 110

4. In a system of electric distribution, a main or charging line, and a local independent line containing translating devices, in combination with an induction-coil having a divided secondary coil, and switch appliances, 120 whereby any desired connection of sections of such coil may be effected. 115

5. In a system of electric distribution, a main-line circuit divided into two branches, one containing a contact-operating magnet 125 and secondary battery, and the other containing the primary coil of an induction-coil, and a set of contacts operated by said magnet.

6. In a system of electric distribution, a polarized armature kept polarized by the current of a main line, in combination with an actuating-magnet for said armature in a branch with a secondary battery, a set of contacts operated by said armature in its movements, 130

and a second branch including the primary coil of an induction-coil, the secondary coil of which delivers electric energy to electric lamps or other devices.

5 7. The combination, with a secondary coil, S, supplying current to the lamp L, or other device, of a shunting-switch, W, for short-circuiting the secondary, thereby saving energy of the primary and relieving strain upon the main line.

8. In a system of electric distribution, the combination, with the main line, of a secondary battery, the primary of an induction-coil, a rheotome or circuit-controller, whereby the 15 battery is alternately polarized from the main-line current and discharged through the pri-

mary of the induction-coil, and a secondary coil connected with a local or sub circuit containing electric lamps, motors, or other translating devices.

20

9. The combination, with the secondary circuit and an electric lamp, or other apparatus connected therewith, of an adjustable reactionary coil for the purpose described.

Signed at Lynn, in the county of Essex and 25 State of Massachusetts, this 22d day of April, A. D. 1885.

ELIHU THOMISON.
